UNITED STATES PATENT OFFICE.

JOSEPH W. LARISH, OF BUFFALO, NEW YORK, ASSIGNOR TO THE BALTIMORE AND OHIO TELEGRAPH COMPANY, OF BALTIMORE, MARYLAND.

CALLING APPARATUS FOR TELEGRAPH-CIRCUITS.

SPECIFICATION forming part of Letters Patent No. 361,365, dated April 19, 1887.

Application filed July 31, 1886. Serial No. 209,613. (No model.)

To all whom it may concern:

Be it known that I, JOSEPH W. LARISH, a citizen of the United States, residing in Buffalo, in the county of Erie and State of New 5 York, have invented certain new and useful Improvements in Calling Apparatus for Telegraph-Circuits, of which the following is a specification.

The invention relates to the class of devices 10 employed for attracting the attention of or calling up the operators upon telegraph-lines.

The object of the invention is especially to provide means whereby the operator at a terminal branch office may attract the attention 15 of an operator at a distant repeating station without calling upon the main office at the home station.

The invention consists in providing, at the station to be called, a harmonic reed or vibrator, and in locating at the point from which it may be desired to produce the call a harmonic transmitter tuned to the same pitch as the receiving-instrument. The transmitter is included in a normally-shunted circuit of 25 the main line; but this shunt-circuit may be interrupted by means of a suitable switch, so that the main-line connections are completed through this transmitter. A series of electrical impulses are thereby sent to line, and 30 these vitalize the electro-magnet of the receiving-instrument with the proper frequency, and cause the harmonic reed to respond and to give a signal to the operator at that station.

The drawing is a diagram illustrating an organization of circuits adapted to carry out the 35 invention.

Referring to the drawing, L represents a main line connecting two distant stations, A' and A²—for instance, New York and Buffalo—40 through a branch or repeating station, A³. The line L is equipped at the terminal stations A' and A² with a proper system of batteries, O' and O², and with the usual transmitting and receiving instruments, as indicated 45 at K' and K² and R' and R². At the repeating or branch office A³, also, there is provided a transmitter and receiver, R³.

For the purpose of attracting the attention 50 of the operator at the Buffalo office—A², for instance—without calling up the operator at the New York station A', there is placed in a branch circuit at the station A³ a harmonic transmitter, D', consisting of an electro-magnet, d', provided with a reed-armature, e',

adapted to vibrate with a given rapidity. 55 The branch line 2, leading from a point, 1, in the main line, includes the coils of an electro-magnet, d', and leads to the armature e'. The resting contact f' of this reed-armature is connected by a conductor, 3, with a point, 60 4, in the main line L. The connections of the main line are normally completed between the point 1 and 4 through a switch or circuit-interrupting device, M', which may be moved so as to sever the connections and cause the 65 main-line current to traverse the branch circuit, including the electro-magnet d'. This magnet will then be vitalized and cause a series of impulses to be sent upon the line depending upon the tone to which the reed-armature is adapted to respond. Such impulses 70 traverse, at the distant station A², an electro-magnet, d², provided with a reed-armature, e², tuned to the same tone as the armature e'. These electrical interruptions or impulses will 75 cause the armature e² to be set in motion, and thus give a tone attracting the attention of the operator at that station. It will be evident, however, that the armature e² will not respond to the ordinary movements of the keys 80 employed for working the instruments upon the main line.

I claim as my invention—

1. The combination, substantially as hereinbefore set forth, with a main line and telegraph transmitting and receiving apparatus, of a harmonic transmitter, a normally-shunted branch circuit including the same, means for placing said branch circuit in the direct circuit of the main line, and a harmonic receiver responding to the electrical vibrations established by said harmonic transmitter. 85

2. The combination, substantially as hereinbefore set forth, with a main line and telegraph transmitting and receiving apparatus included therein, of a harmonic transmitter, a normally-closed shunt-circuit, a harmonic receiver at a distant station, tuned to the same pitch as the transmitter and included in the main-line circuit, substantially as described. 95

In testimony whereof I have hereunto subscribed my name this 14th day of July, A. D. 1886.

JOSEPH W. LARISH.
